Primary Examiner—Ian Simmons*Assistant Examiner*—Dana Sipos(74) *Attorney, Agent, or Firm*—Brinks Hofer Gilson & Lione(57) **CLAIM**

I claim the ornamental design for a bottle, as shown and described.

DESCRIPTION

FIG. 1 is a side elevation view of a bottle showing the present invention, the opposite side being a mirror image thereof.

FIG. 2 is a plan view from the bottom of FIG. 1.

FIG. 3 is a plan view from the top of FIG. 1.

FIG. 4 is a fragmentary cross-sectional view taken along the line 4—4 of FIG. 2; and,

FIG. 5 is an elevated perspective view of the bottle shown in the previous Figures.

The broken lines shown in the drawings are for illustrative purposes only and form no part of the claimed design.
